HAND HELD REMOTE RADIO CONTROL UNIT

Raymond F. Pitman, Prairie Village, Kans. and William T. Dale, Euless, Tex., assignors to R O Products, Inc., Olathe, Kans.

Filed Apr. 5, 1974, Ser. No. 458,246

Term of patent 14 years

Int. Cl. D13—03

U.S. Cl. D26—13 C

Fig. 1.

Fig. 2.

Fig. 3.

Fig. 4.

Fig. 5.

Fig. 6.

FIG. 1 is perspective view of a hand held remote radio control unit showing our new design, the antenna being in the erected position;

FIG. 2 is a top plan view of same with the antenna retracted;

FIG. 3 is a side elevational view of same, the other side being substantially the same in appearance;

FIG. 4 is a bottom plan view of same;

FIG. 5 is an end view of same taken from the right end of FIG. 3; and

FIG. 6 is an end elevational view of same taken from the left end of FIG. 3.

We claim:

The ornamental design for a hand held remote radio control unit, as shown and described.
